Inventor,

Hairy C. Adam

UNITED STATES PATENT OFFICE.

HARRY C. ADAM, OF ST. LOUIS, MISSOURI.

DESIGN FOR A LIGHTING-FIXTURE.

51,326.

Specification for Design.

Patented Oct. 9, 1917.

Application filed July 19, 1917. Serial No. 181,657. Term of patent 14 years.

To all whom it may concern:

Be it known that I, **HARRY C. ADAM**, a citizen of the United States, residing at St. Louis, Missouri, have invented a certain new, original, and ornamental Design for a Lighting-Fixture, of which the following is a specification, reference being had to the accompanying drawing, forming part thereof.

Figure 1 of the drawings is a side elevational view of my new ornamental design for a lighting fixture, and Fig. 2 shows plan

and ornamentation on back plate thereof, one half only of ornamentation on back plate being shown.

I claim:

The ornamental design for a lighting fixture, as shown.

HARRY C. ADAM.

Witnesses:

**R. M. TREXLER,
G. W. JOHNSON.**
